UNITED STATES PATENT OFFICE.

MICHAEL W. MCARDLE, OF CHICAGO, ILLINOIS.

DESIGN FOR A STORAGE AND CARRYING CASE.

Application filed July 9, 1926. Serial No. 18,283. Term of patent 14 years.

To all whom it may concern:

Be it known that I, MICHAEL W. MCARDLE, a citizen of the United States, residing at Chicago, in the county of Cook and the State of Illinois, have invented a new, original, and ornamental Design for a Storage and Carrying Case, of which the following is a specification, reference being had to the accompanying drawings forming a part thereof.

The drawing is a perspective view of a storage and carrying case embodying my

new design, in which it will be noted that the characteristic feature is the appearance of heavily riveted or studded construction, resembling that of an ancient treasure chest.

I claim:

The ornamental design for a storage and carrying case substantially as shown and described.

In testimony whereof, I have hereunto set my hand this sixth day of July, 1926.

MICHAEL W. MCARDLE.
